RECIRCULATING STABILIZER PUMP

Theodore R. Dinsmore, Dayton, Ohio, assignor to
 Curtis Pump Company, Dayton, Ohio, a corpora-
 tion of Ohio

Application August 7, 1944, Serial No. 548,345

9 Claims. (Cl. 103—113)

This invention relates to pump devices which separate vapors from liquids and repeatedly treat liquids before they are pumped to insure delivery of fully liquid material.

Specifically, the invention deals with a fuel recirculator attachment for a booster pump of an airplane fuel system.

In accordance with this invention, a vapor and liquid separating booster pump is mounted in the fuel tank of an airplane to be submerged in fuel in the tank. The pump is equipped with centrifugal pumping vanes and axial flow vanes to circulate bubble-rich liquid out of the pump so that the centrifugal pumping vanes will not become gas-bound. An axial flow stream of fuel is created locally in the tank and this stream is deflected to flow back to the pump. Bubbles entrained in the stream are permitted to rise in the pond of fuel in the tank for bursting at the surface of the pond to liberate the gases and vapors therefrom. The fuel, including recirculated fuel, is screened before it can reach the inlet of the pump, so that any occluded bubbles are prevented from passing back to the pump with the liquid.

Since the tank is vented to the atmosphere, and can discharge the liberated gases and vapors out of the tank vent, continued treatment of the liquid fuel in the tank by the vapor separating pump results in the creation of a stabilized fuel freed from vapors produced by volatiles which gasify at rarefied high altitude atmospheres. The continued recirculation and repeated agitation of the fuel by the pump thus produces locally in the tank a stabilized fuel which is eventually pumped into the fuel line of the fuel system. Vapor lock in the fuel system is thereby eliminated since only a stabilized, vapor and gas-free, liquid fuel is delivered into the fuel line.

It is, then, an object of this invention to provide a pump assembly which subjects liquid to a plurality of vapor-separating operations before pumping the liquid.

A further object of the invention is to provide a pump which stabilizes volatile liquid material before pumping it.

Another object of the invention is to provide a booster pump especially adapted for airplane fuel systems which stabilizes liquid fuel by repeatedly agitating the fuel before pumping it.

A still further object of the invention is to recirculate fuel in a tank through a vapor-separating pump for stabilizing the fuel.

Another object of the invention is to equip a vapor-separating booster pump with a recirculating

shield for directing liquid passed through the pump back to the pump.

Other and further objects of the invention will be apparent to those skilled in the art from the following detailed description of the annexed sheet of drawings which, by way of preferred example only, illustrates one embodiment of the invention.

On the drawing:

Figure 1 is a broken fragmentary vertical cross-sectional view with parts in elevation, of a booster pump according to this invention mounted in a fuel tank.

Figure 2 is a horizontal cross-sectional view, with parts in plan, taken along the line II—II of Figure 1.

Figure 3 is a plan view of the deflector shield, of the pump, and showing a part in horizontal cross section.

As shown on the drawing:

In Figure 1, the reference numeral 10 designates generally a tank such as an airplane fuel tank. The tank 10 contains a pond P of liquid fuel such as gasoline or other volatile liquid.

The tank 10 has a bottom wall 11 apertured as at 11a and receiving thereon around the aperture 11a thereof a mounting ring 12.

A pump and motor unit 13 has a base 14 mounted on the outside of the tank bottom wall 11 to cover the aperture 11a thereof. This base 14 receives cap screws 15 therethrough at spaced intervals therearound. These cap screws are threaded into the mounting ring 12 to suspend the unit 13 in the tank.

As shown in Figure 1, the base 14 has an aperture therethrough closed by a bottom cap 16. The cap 16 is secured to the base 14 by means of cap screws 17. A drain plug 18 is provided in the cap 16. A gasket such as 19 is interposed between the base 14 and the cap 16. An additional gasket (not shown) can be interposed between the tank wall 11 and the base 14.

The apertured base plate 14 and the cap 16 cooperate to define a sump S beneath the bottom 11 of the tank 10.

The base 14 has an upstanding open ended tubular portion 20 integral therewith and projecting into the tank 10. This tubular portion 20 receives a conduit fitting 21 on the bottom end thereof together with a cap 22 on the top end thereof. A single bolt 23 is passed through the fitting 21 and is threaded into the cap 22 to secure the cap and fitting to the end of the tubular portion 20. The cap and fitting are 55 interchangeable so that the passageway 20a pro-

vided by the tubular portion 20 can discharge into an inside tank fitting or an outside tank fitting as shown.

As shown in Figure 2, a pair of ribs 24 extend upwardly at an angle to a head 25 best shown in Figure 1. The head 25 supports a motor casing 26 in which is mounted an electric motor having an armature rotating a drive shaft 27. The drive shaft 27 projects through a collar portion 25a of the head. A stationary seal ring 28 is mounted in this collar portion 25 and cooperates with a rotating seal ring 29 driven by the shaft 27 to seal the motor in the casing 26 from liquid of the pond P. As shown, the rotating seal ring 29 has a rubber sleeve 30 clamped therearound by means of a metal cap 31 and this rubber sleeve is held on the shaft by means of a ring or hoop 32. The rubber ring prevents leakage along the shaft through the rotating seal ring 29. The cap 31 is driven through a keyed connection 33 with a member held on the shaft. A spring 34 urges the rotating ring 29 into sliding face engagement with the stationary ring 28.

A leg 35 depends from the head 25. A volute ring 36 is integral with the bottom end of the leg 35 and has ribbed connection with the base plate 14 as at 37. A tubular portion 38 connects the volute ring with the upstanding tubular portion 20. This portion 38 is hollow and serves as a passageway for conducting fluid from the volute chamber 39 of the ring 36 to the passageway 20a in the tubular portion 20.

The ring 36 has an open bottom end above the cap 16 receiving a throat ring 40 therein. Cap screws such as 41 secure the throat ring to the volute ring.

A pump impeller, indicated generally by the reference numeral 41, is mounted in the volute ring. This impeller 41 includes a hub 42 secured on the bottom end of the shaft 27. This hub is joined through helical axial flow-producing vanes 43 with a collar member 44 riding in the upper end of the throat ring 36. The collar member 44 has an outturned flange 44a at the bottom end thereof from which depends a plurality of spaced centrifugal pumping vanes 45. The pumping vanes 45 extend downwardly to the inlet opening 40a of the throat ring 36 and have radially extending portions communicating with the volute chamber 39 of the ring 36.

The impeller 41 thus cooperates with the volute ring 36 and the throat ring 40 to provide a central chamber through the pump with the lower end of the chamber in full open communication with the sump S, and with the top of the chamber having the vanes 43 therein to create an axial flow through the chamber. The vanes 43 are pitched to induce axial flow through the chamber. The vanes 45 are curved for centrifugal discharge from the axial flow chamber into the volute chamber 39. Liquid under pressure in the volute chamber 39 is flowed through the tubular portion 38 into the passageway 20a from which it is discharged through the conduit fitting 21 to the fuel line of the airplane fuel system.

As shown in Figures 1 and 2, a cylindrical screen 47 is bottomed on the base plate 14 and extends upwardly therefrom above the level of the volute ring 36. The upper end of the cylindrical screen 47 is covered with a flat screen disk 48 which is secured to the screen 47 by means of angle brackets 49 and screws 50 at spaced intervals therearound. As shown, an angle bracket 51 and screw 52 connect the inner portion of

the screen disk 48 to the leg 35. A similar connection is made by an angle bracket 53 and a screw 54 to a boss 55 on the volute ring 36.

The screen disk 48 does not overlie the axial flow vanes 43.

A deflector shield 56, best shown in Figures 1 and 3, fits snugly around the collar portion 25a of the head 25 and is suspended from the head by means of a leg 57. Notches 58 are cut into the periphery of the shield member 56 to straddle the ribs 24. The shield can be soldered or otherwise secured to these ribs if desired.

As shown in Figure 3, the shield is in the form of a dished disk which, as indicated in Figure 1, provides an umbrella-like deflector in spaced relation above the axial flow vanes 43 and the screen disk 48.

In operation of the unit 13, the motor in the casing 26 drives the shaft 27 to rotate the impeller 41. Liquid from the pond P in the tank 10 flows by gravity into the sump S and through the opening 40a of the throat ring 36 into the open ended chamber provided through the volute ring and impeller. The vanes 43 create a large volume axial flow of liquid in an upward direction through the central chamber of the pump and this liquid, as indicated by the arrows in Figure 1, is deflected by the shield 56 downwardly toward the screen disk 48.

The centrifugal pumping vanes 45 centrifugally discharge some of the liquid flowing axially through the pump into the volute chamber 39. Since this liquid is quite volatile and since the vanes 45 agitate the liquid, bubbles of gas and vapor are liberated from the liquid and, being lighter than the liquid, are not thrown radially outwardly into the volute chamber but collect along the inner ends of the vanes 45 to be entrained in the axial flow stream of liquid created by the vanes 43. Bubbles B thus flow upwardly, with the liquid issuing out of the top end of the impeller, to the deflector 56. The bubbles B being lighter than the liquid however, will rise through the pond P as soon as they clear the outer peripheral edge of the deflector 56. Some bubbles might be entrained with the downwardly flowing liquid to the pump, as indicated in Figure 1, but the screens 47 and 48 prevent bubbles from being fed back to the pump for re-entry into the pump. The mesh of the screens is fine enough so that bubbles cannot pass therethrough.

Since the axial flow vanes 43 circulate more liquid through the pump than is circulated into the volute chamber by the centrifugal vanes 45, an excess of liquid is moved locally in the pond P around the pump, and this liquid is recirculated back to the pump by the shield 56. Thus, volatile liquids such as gasoline are subjected to repeated agitation before being pumped into the fuel line and become stabilized since their volatiles, which are about to gasify, are removed from the liquid in the form of liberated bubbles which rise through the tank and burst at the surface of the tank.

As a result, when an airplane flies to high altitudes and volatiles in the vented fuel tank thereof become successively more unstable, the pump of this invention will condition the fuel to actually release these volatiles before they can gasify in the fuel line. Vapor lock in the fuel line is eliminated, and the fuel is stabilized for high altitude consumption.

From the above descriptions it will be understood that the invention provides a vapor-separating pump which recirculates liquid so that the

liquid is repeatedly subjected to a vapor separating treatment before it is pumped, thus producing a stabilized, fully liquid material for pumping.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A pump for separating gases and liquids which comprises pumping vanes for centrifugally discharging liquids, means for circulating liquids through the pump along the pumping vanes to prevent the pumping vanes from becoming gas-bound, and a deflector spaced from said means in the path of liquids flow therefrom and cooperating with said means to recirculate the liquids back to the pumping vanes.

2. A vapor-separating pump comprising means defining a volute chamber having a central inlet, and a central outlet, an impeller having pumping vanes for centrifugally impelling liquid from the inlet to the volute chamber together with flow vanes for flowing liquid from the inlet to the central outlet for sweeping liberated vapors away from the pumping vanes, and a deflector shield in spaced relation from said flow vanes for directing the liquid impelled thereby back to the central inlet.

3. A stabilizing pump which comprises a casing having a central inlet, an annular pumping chamber, and a central outlet, an impeller rotatably mounted in said casing having pumping vanes for discharging liquid from the inlet to the pumping chamber together with additional vanes for flowing liquid from the inlet to the central outlet for sweeping bubbles of vapors out of the pump, a deflector shield mounted in the path of liquid discharged from the central outlet for deflecting said liquid back to the pump inlet, and a screen interposed between said shield and the pump inlet for preventing passage of bubbles therethrough.

4. In combination with a tank having an apertured bottom wall, a pump and motor unit in said tank having a base closing the aperture of said tank wall and defining a sump for the tank, the pump of said unit having an open-ended vertical passageway above said sump with a pumping chamber around the passageway in communication therewith intermediate the open ends thereof, the motor of said unit being spaced above the top end of said passageway, an umbrella-shaped deflector between the motor and top end of the passageway arranged to deflect liquids rising from the passageway back to the sump, a shaft depending from the motor and driven thereby, an impeller on the shaft having a ring of circumferentially spaced pumping vanes in the passageway arranged for pressuring liquids from the passageway into the pumping chamber and for agitating the liquids to liberate bubbles of gas and vapor therefrom, said impeller also having blades for flowing liquids through the passageway and out of the top end thereof to sweep the bubbles out of the pump toward the deflector and a screen between the tank and sump having a mesh arranged for pre-

venting passage of bubbles in the deflected liquid back to the passageway.

5. In combination, a tank, a pump in said tank having a free flow passage therethrough open at both ends to the interior of the tank, an agitating impeller rotatably mounted in the passage to centrifugally pump liquids therefrom and to liberate gases and vapors from the liquids, a propeller for flowing large volumes of liquid from the tank through the passage and back to the tank to sweep out the bubbles of gas and vapor liberated by the impeller, and a deflector shield in the tank arranged for recirculating liquids in the tank from the passage back to the passage to repeatedly treat the liquids before they are centrifugally pumped.

20 6. A submerged pump and motor unit comprising vertically spaced pump and motor casings, said pump casing being below the motor casing and having an open ended free flow passage therethrough and a pumping chamber there-around in communication with the passage, said motor casing having a motor shaft extending therefrom, a pump impeller on the shaft in the passage having centrifugal pumping and agitating vanes for pressuring liquids from the passage into the pumping chamber and for liberating bubbles of gas and vapor from liquids together with flow vanes for flowing liquid and occluded bubbles through the passage, and a deflector between the pump and motor casings arranged for recirculating liquids from the passage downwardly back to the passage while allowing bubbles in the liquid to rise above the deflector.

35 7. A vapor separating pump comprising a pump casing having a vertical passageway therethrough open at the top and bottom and a pumping chamber surrounding the passageway in annular communication therewith, agitating pumping vanes in the passageway, and means for repeatedly circulating liquid through the passageway to pretreat the liquid before it is pumped.

40 8. A liquid stabilizing assembly which comprises a tank for containing a pool of liquid, a pump in said tank having an inlet and an axial outlet communicating with a pool of liquid in the tank, said pump having a peripheral outlet communicating with the exterior of said tank, an impeller in said pump for discharging liquid from the inlet to the peripheral outlet, a second impeller in said pump for flowing liquid from the inlet through the axial outlet back to said pool of liquid in the tank, and a deflector device in said tank spaced from said axial outlet in the path of liquid flow therefrom for recirculating liquid from the axial outlet back to the inlet.

45 9. A pump and tank assembly comprising a tank for a pond of liquid, a pump casing in said tank having a passageway communicating at both ends thereof with liquid in the tank, pumping vanes in said casing for pressuring liquids from said passageway, flow vanes for circulating liquids and bubbles released by the pumping vanes through the passageway out of the pump and back to the pond of liquid in the tank, and a deflector in said tank in the path of liquid flow from the passageway to direct the thus circulated liquids back to the pump.

THEODORE R. DINSMORE.
